UNITED STATES PATENT OFFICE.

MAGGIE DAVENPORT, OF IONIA, MICHIGAN.

RACK.

Application filed December 30, 1922. Serial No. 609,899.

To all whom it may concern:

Be it known that I, MAGGIE DAVENPORT, a citizen of the United States, residing at Ionia, in the county of Ionia and State of Michigan, have invented certain new and useful Improvements in Racks, of which the following is a specification.

My invention relates to improvements in racks, primarily adapted for supporting 10 bake pans, either within the stove oven or upon the stove surface for permitting two or more pies, cakes or the like to be baked within the same oven for thereby constituting a saving of time.

15 My improved article may be further employed as a dry rack for pots and pans and the same is characterized by its simplicity of construction, cheapness of manufacture and usefulness of purpose.

20 In the drawing forming part of this application, like numerals of reference indicate similar parts in the several views, and wherein:

25 Figure 1 is a perspective view of a rack constructed in accordance with the present invention.

Figure 2 is a plan view of one of the metallic cross strips employed in connection with my invention and,

30 Figure 3 is a similar view of one of the rack supporting legs.

Having particular reference to the drawings, my improved rack constitutes the provision of a pair of similar shaped metallic 35 strips or bars 1 extending at direct right angles to each other and centrally joined together by a rivet or the like 2, each bar or strip being formed with a central opening 3 for this purpose.

40 The opposite ends of each member 1 are formed with an upstanding ear 4, these ears being formed by bending opposite corners of opposite ends of the strips upwardly at direct right angles thereto and upon a line 45 of substantially forty-five degrees with respect to the longitudinal axis of the strips, as designated by the dotted lines *a* in Figure 2.

Each ear 4 has a central opening 5 and 50 has secured thereto, a vertical leg 6 of a nature substantially shown in Figure 3, each leg being also provided with a central opening 7, whereby through the instrumentality of a rivet 8, the said legs are secured to the 55 said ears 4. In view of the specific formation of the ears 4 upon opposite ends of the

cross strips or bars 1, it will be readily seen that the legs 6 upon the opposite ends of each strip or bar 1 will be in true face to face relation with each other, for thereby 60 providing a more rigid support for these cross bars.

The opposite ends of each of the legs 6 are formed with additional openings 9 for permitting a similar rack to be attached to the 65 upper end of the leg members for purposes hereinafter described.

If desired, the rivet 2 for the cross bars or strips 1, may be loosely disposed, so as to function as a pivot pin for permitting the 70 said legs to be folded, and the same may be true of the rivets 8 for permitting the legs 6 to be swung lengthwise with respect to the bars whereby the rack may be so folded as to be stored within a small compass. 75

In the practical use of my device, the rack is set up as shown in Figure 1, and if to be employed in an oven, a pie or cake pan may be supported directly upon the top surface of the cross bars or strips 1, the rack being 80 positioned over a smaller pie or cake pan upon the floor of the oven and if desirable, another rack may be secured to the first mentioned rack by inserting pins through the openings 9 in the legs of each rack, this second rack, also adapted for the support of a 85 pie or cake pan.

While I have herein shown and described the preferred embodiment of the present invention, it is nevertheless to be understood 90 that minor changes may be made therein, without departing from the spirit and scope of the invention as claimed.

What I claim as new is:

A rack comprising a pair of metal strips 95 arranged in cruciform relation and secured to each other at points midway between their ends for pivotal movement, the end portions of the strips being bent to provide securing tabs, said tabs being disposed in 100 planes at acute angles to the median longitudinal dimensions of the strips and legs fixed to the outer surfaces of the tabs and disposed transversely across the ends of the strips, said legs being of flat material and 105 having inner vertical edges disposed within the extremities of the strips and outer vertical edges disposed beyond the extremities of the strips.

In testimony whereof I affix my signature.

MAGGIE DAVENPORT.
